UNITED STATES PATENT OFFICE.

PATRICK BROWNLEY, OF ST. JOHN, NEW BRUNSWICK, CANADA, ASSIGNOR
OF ONE-HALF TO JAMES STRATON, OF SAME PLACE.

JOURNAL-BOX FOR RAILWAY-CARS.

SPECIFICATION forming part of Letters Patent No. 412,723, dated October 15, 1889.

Application filed March 5, 1889. Serial No. 301,838. (No model.)

To all whom it may concern:

Be it known that I, PATRICK BROWNLEY, of St. John, in the county of St. John, Province of New Brunswick, Dominion of Canada, have 5 invented a certain new and useful Improvement in Journal-Boxes for Railway-Cars, of which the following is a description sufficiently full, clear, and exact to enable any person skilled in the art or science to which 10 said invention appertains to make and use the same, reference being had to the accompanying drawings, forming part of this specification, in which—

Figure 1 is a vertical longitudinal section 15 of a car journal-box provided with my improvement; and Fig. 2, a vertical transverse section of the same, taken on line xx in Fig. 1.

Like letters and figures of reference indicate corresponding parts in the different figures of the drawings.

My invention relates to that class of journal-boxes in which the journals are automatically lubricated; and it consists in certain novel features, as hereinafter fully set forth 25 and claimed, the object being to produce a simpler, cheaper, and more effective device of this character than is now in ordinary use.

The nature and operation of the improvement will be readily understood by all 30 conversant with such matters from the following explanation.

In the drawings, A represents the body of the journal-box, which is supported on the car in the usual manner, and B the axle. The 35 axle is reduced at its outer end, forming the journal C between a shoulder b and annular flange d.

The body A is preferably rectangular in cross-section, and to a bed-piece f in the top 40 thereof is secured a bushing g, which bears upon the journal C. A longitudinally - arranged partition h is secured within the box below the journal, forming a chamber D, for receiving waste or packing. The space between the partition h and the bottom i of the box forms an oil-reservoir G, hereinafter described, the bottom i being inclined outwardly, as shown in Fig. 1.

A circular or nearly circular box H is secured 50 to the outer end of the body A by bolts l, passing through lugs m on said body, the journal-

flange d projecting through an opening in the inner box-wall. The box is provided with a door p in its outer face, and may be cast integral with the body A, if preferred, instead 55 of being bolted thereto. An arm t is secured centrally to the end of the journal C, and is revolved thereby in the chamber v of the box H, said arm being provided with a forked head w, Fig. 2, the prongs of which may curve 60 or slope laterally, after the manner of propeller-wings. An opening 15 connects the packing-chamber D with the box-chamber v, through which the packing may be passed, said opening being closed by a door 16 at its 65 outer end.

A longitudinally - arranged inwardly - inclined distributing-shelf 17 is secured within the body A at each side of the journal C, an inwardly-inclined duct 18 leading from the 70 chamber v of the box H onto each shelf 17.

In the use of my improvement the reservoir G is supplied with oil or other lubricant, a portion of which is discharged therefrom into the box H. As the axle revolves, the agitating-arm t rotates in the chamber v of said box. The forked head w of said arm carries the lubricant with it from the reservoir, and a portion thereof, clinging to the walls of the chamber v, runs back into the ducts or gutters 18, thence it runs onto the shelves 17, and, as said shelves are inclined rearwardly 80 as well as inwardly, the lubricant is thereby distributed continually onto the journal and packing in the chamber D. Should the oil 85 overflow the chamber D, it will pass downward through conductor 19 at the rear of said box into the reservoir or over the front of said packing-chamber into chamber v.

It will be seen that the arm t constantly 90 raises the lubricant and supplies it directly to the bearings, thus obviating the liability of these parts becoming overheated.

I do not confine myself to employing packing in the chamber D, as the device can be 95 used without it in many cases and still keep the journal sufficiently lubricated.

Having thus explained my invention, what I claim is—

1. In a journal-box of the character described, the combination of a body provided with a bushing in its upper portion, a hori- 100

zontal partition below the axle-opening, forming a packing-chamber and lubricant-reservoir, inwardly-inclined distributing-shelves above said packing-chamber, a box on the 5 outer end of said body, into which the reservoir opens, ducts leading from said box onto said shelves, and an arm secured to the journal and fitted to rotate in said box, substantially as and for the purpose set forth.

10 2. In a device of the character described, the combination of a body, a bushing bearing upon the axle-journal, a box in the outer end of said body provided with a door, a packing-chamber in said body opening into said box, 15 a door for said chamber, a reservoir in the body opening into said box, ducts leading from said box onto inwardly-inclined distributing-shelves in the body, and a laterally-projecting arm on said journal fitted to rotate 20 in said box and raise the lubricant to said ducts, substantially as described.

3. In a journal-box, a body provided with a bushing for supporting it on an axle-journal, a box on said body provided with a door, an 25 oil-reservoir leading into said box, ducts leading from the box onto inclined shelves in the body for distributing the lubricant onto the journal, and an arm fixed to the outer end of the journal and rotating in said box, said arm 30 having a forked head, whereby the lubricant from the reservoir may be conveyed to said ducts, substantially as described.

4. In a journal-box, a body provided with a bushing bearing on the axle-journal, a circular box on the outer end of said body pro-

vided with a door, a packing-chamber below said journal opening into said box, an oil-reservoir opening into said box and provided with an outwardly - inclined bottom, ducts leading from said box onto inwardly-inclined 40 distributing-shelves in said body, and an arm projecting laterally from the outer end of said journal and fitted to rotate in said box, said arm having a forked head provided with curved prongs, whereby oil from the reservoir 45 may be conveyed to said ducts, substantially as described.

5. In a journal-box, the axle-journal C, provided with the flange d, in combination with the body A, having the bushing g, the box H 50 on said body, the reservoir G, opening into said box, the inclined shelves 17, the ducts 18, leading from said box to said shelves, and the arm t, secured to said journal, all being arranged to operate substantially as described. 55

6. In a journal-box, the combination of the axle B, the body A, having the bushing g bearing on the journal C, the box H, provided with the inclined bottom i and door p, the partitions h, forming packing-chamber D and 60 reservoir G, opening into said box, the door 16 for said chamber, the ducts 18, leading from said box to inclined distributing-shelves in said body, and the arm t, provided with the forked head w, substantially as and for the 65 purpose set forth and described.

PATRICK BROWNLEY.
